(57) **CLAIM**

The ornamental design for an immunochromatographic test device, as shown and described.

DESCRIPTION

FIG. 1 is a front right perspective view of an immunochromatographic test device according to the present invention. FIG. 2 is a front view of the immunochromatographic test device of FIG. 1.

FIG. 3 is a rear view of the immunochromatographic test device of FIG. 1.

FIG. 4 is a top view of the immunochromatographic test device of FIG. 1.

FIG. 5 is a bottom view of the immunochromatographic test device of FIG. 1.

FIG. 6 is a right side view of the immunochromatographic test device of FIG. 1; and,

FIG. 7 is a left side view of the immunochromatographic test device of FIG. 1.

The broken lines shown in the figures represent portions of the immunochromatographic test device that form no part of the claimed design.
